FILLING FEELER MECHANISM FOR LOOMS

Filed Feb. 13, 1929

UNITED STATES PATENT OFFICE

JONAS NORTHROP, OF HOPEDALE, MASSACHUSETTS, ASSIGNOR TO STANDARD LOOMS, INC., OF SPARTANBURG, SOUTH CAROLINA, A CORPORATION OF SOUTH CAROLINA

FILLING-FEELER MECHANISM FOR LOOMS

Application filed February 13, 1929. Serial No. 339,646.

The present invention relates to filling feeler mechanisms for looms.

The object of the present invention is to provide a feeler mechanism of small size and of simple and inexpensive construction which is highly sensitive and which will not cause appreciable wear on the yarn. To this end, the present invention consists of the filling feeler mechanism hereinafter described and particularly defined in the claims.

In the accompanying drawings, Fig. 1 is a perspective view of the preferred form of mechanism of the present invention; Fig. 2 is a plan view of the feeler assembly with the cover removed; Fig. 3 is a plan view of the feeler showing the feeler engaged by a supply of filling; Fig. 4 is a plan view of the feeler shown in engagement with a nearly exhausted bobbin; Fig. 5 is a section on line 5-5 of Fig. 2; and Fig. 6 is a sectional detail view being taken on the line 6-6 of Fig. 1.

The illustrated embodiment of the invention comprises the body 8 of the feeler, supported as usual on a bracket 10. The feeler mechanism is enclosed by the body 8 and a cover or cap 12. The feeler comprises a rearwardly extending wire 14 having the triangular filling feeling tip or engaging head 16 provided on its rear face with notches 18. The body is recessed at 19 to provide a space in which the feeler is free to slide. The feeler is formed internally of the body with a right angle portion 20 which at its end 21 is turned down to form a pivotal mounting for the feeler in the sliding block 22. The block 22 has a depending guide projection 24 which slides in a longitudinal slot 26 of the body. The block is extended toward the feeler, that is, toward the left as shown in the drawings, to provide a circular spring abutment 28 which is transversely slotted to receive the portion 20 of the feeler. Extending forwardly from the abutment 28 are a pair of tapered projections 30 adapted to embrace the feeler and to maintain the latter in proper

position when it is permitted to turn on the pivot 21. The circular spring abutment 28 is free to slide in a longitudinal circular recess formed by a groove 32 of the body and a similarly formed registering groove 33 of the cover. The abutment is preferably maintained out of frictional contact with the walls of the circular recess, the block being supported at its lefthand end by means of a projection 34 which slides on the portion 19 of the body adjacent to the groove 32. The circular recess accommodates a compression spring 36 which engages at one end the forward wall 38, and at the other end the transverse portion 20 of the feeler and the abutment 28. The spring is preferably tapered toward the forward end of the body in order that there may be practically no opportunity for any of the coils of the spring to engage frictionally with the adjacent surfaces of the body and cover.

As shown in Fig. 2, the recess 19 of the body in which the feeler works forms a shoulder 42 which serves to position the feeler and prevent wobbling thereof on a normal movement. As shown in Fig. 3, when the feeler is engaged by a working supply of filling on the bobbin, the feeler is pushed straight forward, being prevented from slipping by the engagement of the yarn with the notches 18. The block 22 slides forwardly against the compression of the spring 36. Wobbling of the feeler with consequent wear on the yarn is prevented by the tendency of the slide to move substantially parallel to itself at all times against the action of the spring, and also by the slight frictional engagement of the feeler with the shoulder 42. When a spent bobbin is presented to the feeler, the feeler slips over the smooth surface toward the left or the butt of the bobbin, as shown in Fig. 4. The feeler, not being now restrained by the filling, turns on the pivot, the slipping tendency being sufficient to overcome the pressure of the

spring on the transverse portion 20 of the feeler.

The feeler preferably operates to slip toward the butt of the bobbin rather than toward the small end for the reason that the feeler may then be mounted to engage the filling farther from the butt. It is an advantage to feel of the filling as far from the butt as possible, in order that the filling 10 originally subjected to the feeling action may run off as early as possible, thus presenting fresh yarn to the feeler. Thus a better distribution of wear on the filling is obtained.

The side slipping motion of the feeler is 15 transmitted to the change mechanism in the following manner: The body is provided with a transverse slot 46 and the cap is provided with a registering slot 48, both of which are arranged to accommodate a depending portion 50 of a pull rod 52. The rod is provided with a hook end 54 to lie under the feeler. The other end of the rod hooks into a pivoted latch 56 which is mounted on a bracket 58 projecting from the 25 horizontal actuator 60. The actuator is connected in the usual manner with the change mechanism. The latch 56, as shown in Figs. 1 and 6, is formed with an integral pin or stud 62 adapted to be received in a corresponding hole of the bracket 58. The pin 62 has a projecting tail 64 which may be passed through a similarly formed opening 66 to permit attachment or removal of the latch without the necessity for using cotter pins or other securing expedients. The latch 30 has a striking portion 68 the end of which moves through a vertical opening 70 in the actuator 60. The latch normally lies below the path of movement of the cam follower 35 72 which is oscillated in the usual manner once for every two beats of the lay. The cam follower normally passes through a vertical opening 74 in the bracket 58. When the feeler slips, however, the rod 52 pulls 40 the latch up into the path of the cam follower which then pushes the actuator 60 forwardly to initiate the operation of the bobbin transfer mechanism in any suitable manner.

The rod 52 is formed with a bend 76 immediately above the feeler. The effective 45 length of the rod between the feeler and the latch, and hence the extent of movement of the latch as well as the sensitivity of the feeler may be adjusted by varying the angle 50 of the bend. The bend lies in a horizontal plane. This construction offers an advantage over adjustable rods in which the folds are in a vertical plane, because adjustment of the latter almost invariably causes canting 55 of one of the portions of the rod at one side of the bend, thus necessitating a further adjustment.

The feeler of the present invention commends itself because of its small frictional 60 resistances, which conduce to sensitive action

and prevent undue wear on the filling. Transverse wobbling of the feeler during a feeling movement is prevented both by the guiding of the block 22 in the slot 26 and by the depending pivot end 21 of the feeler. 70 Moreover, the pivot 21 maintains the feeler always in a horizontal plane, thus preventing vertical vibration which might bring about excessive wear on the filling.

Having thus described the invention, what 75 is claimed is:

1. A filling feeler mechanism for looms having, in combination, a body, a slipping feeler extending rearwardly from the body and having a transverse portion within the body, a block adapted to slide longitudinally within the body, the end of the transverse portion of the feeler being pivoted in the block, said body having a longitudinal spring recess, a spring engaging abutment for the block and having provision for engagement with the transverse portion of the feeler, and a compression spring engaging with the abutment to press the block and the feeler rearwardly. 80 85 90

2. A filling feeler mechanism for looms having, in combination, a body, a slipping feeler extending rearwardly from the body and having a transverse portion within the body, a block adapted to slide longitudinally 95 within the body, the end of the transverse portion of the feeler being pivoted in the block, said body having a longitudinal spring recess, a spring engaging abutment for the block and having provision for engagement with the transverse portion of the feeler, and a compression spring engaging with the abutment to press the block and the feeler rearwardly, the spring being tapered from the 100 abutment forwardly to prevent engagement 105 of the coils of the spring with the walls of the recess. 110

3. A filling feeler mechanism for looms having, in combination, a body and a cover provided with registering longitudinal 115 spring recesses, a slipping feeler having in the body a transverse portion extending across the spring recess, a block adapted for longitudinal sliding movement in the body and provided with a spring abutment in the 120 spring recesses, the transverse portion of the feeler engaging with the spring abutment and being pivoted in the block, and a compression spring positioned between the forward end of the body and the spring abutment to press 125 the feeler rearwardly. 130

4. A filling feeler mechanism for looms having, in combination, a body and a cover provided with registering longitudinal 135 spring recesses, a slipping feeler having in the body a transverse portion extending across the spring recess, a block adapted for longitudinal sliding movement in the body and provided with a spring abutment in the spring recesses, the transverse portion of the 140

feeler engaging with the spring abutment and being pivoted in the block, and a compression spring positioned between the forward end of the body and the spring abutment to press the feeler rearwardly, the abutment being provided with forwardly extending projections to embrace and retain the feeler on a slipping movement.

5 In testimony whereof I have signed my
10 name to this specification.

JONAS NORTHROP.
